Primary Examiner—Janice E Seeger*(74) Attorney, Agent, or Firm*—Van Dyke, Gardner, Linn & Buckhart LLP(57) **CLAIM**

The ornamental design for the table, as shown and described.

DESCRIPTION

FIG. 1 is a perspective view of a table in accordance with the present invention, shown in a lowered state;

FIG. 2 is a side elevation of the table of FIG. 1, with the opposite side elevation being substantially identical;

FIG. 3 is an end elevation of the table of FIG. 1, with the opposite end elevation being substantially identical;

FIG. 4 is a top plan view of the table of FIG. 1;

FIG. 5 is a bottom plan view of the table of FIG. 1;

FIG. 6 is a perspective view of the table, shown in a raised state;

FIG. 7 is a side elevation of the table of FIG. 6, with the opposite side elevation being substantially identical; and,

FIG. 8 is an end elevation of the table of FIG. 6, with the opposite end elevation being substantially identical.
